UNITED STATES PATENT OFFICE

EDWARD B. MALLORY, OF TENAFLY, NEW JERSEY, ASSIGNOR TO WESTINGHOUSE ELECTRIC & MANUFACTURING COMPANY, A CORPORATION OF PENNSYLVANIA

COMBINED SIGNAL SYSTEM

Application filed August 25, 1923. Serial No. 659,257.

My invention relates to a system for broadcasting signals controlled by the time of day.

Broadly stated, it is an object of this invention to control, by broadcasting methods, devices which have hitherto been controlled by 5 clocks.

More specifically stated, it is an object of this invention to broadcast signal radiations the wave lengths of which vary with the time 10 of day so that any receiving apparatus, being tuned to proper wave length, will be energized by the wave radiated by the broadcasting system when the predetermined time of day arrives.

15 The invention also includes providing for an adjustment of the tuning of the receiving apparatus whereby the time of day at which it will be energized may be changed at will. It is another object of the invention to provide 20 a dial such that this change in the adjustment of the receiving device can be automatically made by merely indicating the desired time of day on the dial.

Other objects of my invention, as well as 25 details of construction, will be made more apparent by the following description when taken in connection with the accompanying drawing wherein:

Figure 1 is a diagrammatic illustration of 30 a sending station, and

Fig. 2 is a similar view of a receiving device.

In Fig. 1, an antenna 1 is used to indicate the broadcasting system. It is, however, to be understood that radio waves guided by 35 power lines, or by telephone lines or in any other way, could be used as well as the space radio apparatus illustrated.

The sending apparatus includes a vacuum tube 2 with any usual or convenient system of 40 connections enabling it to maintain oscillations. For example, there may be coil 3 inductively related to a coil 4 in the grid circuit and the power for both coils may be obtained from a battery 5. An inductance coil 45 6 maintains the current of battery 5 steady while the grid, under the influence of coil 4, causes fluctuations in the impedance of the tube 2. Oscillations are thus caused in the circuit including coil 3 and condenser 7. The 50 coil 3, acting on coil 4, causes fluctuations on

the grid. The coils 3 and 4 deliver energy to the antenna. The antenna, beside including the coils 3 and 4, also has a condenser 7 of an adjustable character. The adjustment of the condenser 7 co-operates with the coils 3 and 4 to determine the natural period of the antenna and so determines the wave length of the radiations.

The adjustment of the condenser 7 is controlled by any suitable time mechanism. This 60 is diagrammatically indicated by showing a clock 8, the hour shaft 9 of which is connected by an arm 10 and a link 11 to the adjusting mechanism of the condenser 7. As the clock rotates the shaft 9, the link 11 will be reciprocated and so will cause the condenser 7 to be 65 adjusted, first in one direction and then in the other, whereby the condenser goes through a cycle of values each twelve hours. The wave 70 lengths delivered by the apparatus will, therefore, pass through a corresponding cycle in the same time.

At each station which the broadcasting station illustrated in Fig. 1 is intended to control, any suitable antenna or other receiving 75 circuit is employed. As illustrated in Fig. 2, this circuit includes an aerial 16, an adjustable coil 17, and an adjustable condenser 18. Energized from the coil 17 is a circuit including a rectifier 19 and any suitable translating 80 device. In the practical use of the invention amplifying means would be associated with this circuit, since only unusually strong signals would actuate the translating device illustrated, but, as the invention is not concerned with the details of this circuit, the amplifier has not been shown. For illustration, the translating device is shown as an electromagnet 21. This can control any mechanism 85 which it is desired to have operate at a predetermined time.

The adjustment of condenser 18 is effected by manually moving the hands of a clock dial 22. These hands are not driven by clock work but stay wherever the operator sets them. 95 Any suitable connection between the minute hand and the hour hand that will cause them to move at proper relative speed is all the mechanism needed at the clock face 22. The hour hand is connected by an arm 23 and link 100

24 to the adjusting mechanism of the condenser 18. Setting the hands on the clock face 22, therefore, adjusts the condenser 18. This adjustment gives the receiving system a natural period corresponding to the wave length sent out by the sending system shown 5 in Fig. 1 at the time shown by the clock face 22.

Thus, assuming that the clock face 22 is set 10 to five o'clock, when the clock 8 indicates five o'clock the condenser 7 will tune the sending circuit to sympathy with the receiving circuit.

At five o'clock therefore, the magnet 21 15 will be energized and the mechanism controlled thereby will act. If it is desired that this mechanism act at some other time, the clock face 22 is adjusted accordingly.

It will be obvious that the invention is not 20 limited to the specific mechanism illustrated, but that any time controlled device may be used for adjusting the condenser and that any broadcasting apparatus may be substituted for that illustrated. It will be obvious 25 further that other methods of controlling the wave length of the signalling energy may be used beside the adjustment of a condenser. Although I have not shown all of the possible 30 modifications of my invention it will be apparent to those skilled in the art that various changes may be made in the apparatus illustrated without departing from the spirit and scope of my invention, as set forth in the appended claims.

35 I claim as my invention:

1. In an alarm system, means for generating and radiating oscillatory energy, means for so continuously altering the frequency of the radiated energy that a frequency is allocated to each time division 40 over a range of twenty-four hours, the time divisions within the time-period corresponding to the complete range of frequencies, each having a different frequency allocated thereto, and the time-period corresponding 45 to the complete range of frequencies being so large a fraction of twenty-four hours that the portion of the day corresponding thereto is easily identified, radiant energy reception means including instrumentalities for 50 permitting the energization of an alarm device, and means for tuning said reception means to any frequency in the range of the frequencies of said radiated energy, said 55 tuning means comprising a device that indicates the correlation of the tuning with the said time-divisions, whereby, by properly tuning said receiving device it may be pre-tuned to respond to said transmitted energy 60 at any designated time-division, and an alarm accordingly given.

2. In a signalling system, a radio sending set, means included therein for altering the wave-length sent out by said set, said means 65 producing cyclic changes of wave-length

and time-controlled means for actuating said wave-length-altering means at such speed that the number of cycles of change per day will be sufficiently small to enable the time of day to be recognized from observation of 70 said wave-length.

In testimony whereof, I have hereunto subscribed my name this 18th day of August, 1923.

EDWARD B. MALLORY.
